UNITED STATES PATENT OFFICE.

SALLIE C. HEARD, OF THOMASVILLE, GEORGIA, ASSIGNOR TO RALPH H. NEEL,
LEE NEEL, CLYDE N. NEEL, AND GEORGE R. NEEL, OF THOMASVILLE,
GEORGIA.

HUSK HAT.

SPECIFICATION forming part of Letters Patent No. 717,571, dated January 6, 1903.

Application filed April 7, 1902. Serial No. 101,812. (No model.)

To all whom it may concern:

Be it known that I, SALLIE C. HEARD, a citizen of the United States, residing at Thomasville, in the county of Thomas and State of Georgia, have invented certain new and useful Improvements in Husk Hats; and I do hereby declare the following to be a full, clear, and exact description of the invention, such as will enable others skilled in the art to which it appertains to make and use the same.

This invention aims to utilize corn-shucks in the manufacture of hats, because of the lightness, toughness, and cheapness of this material and the ease with which it can be shaped.

The present invention is a new use for a material usually wasted, and sun-hats are admirably adapted to be made from corn-shucks, because large-brimmed hats are exceedingly light and cool.

The purpose of the invention is to devise a construction whereby corn-shucks can be used as the material entering into the formation of the head-covering. This material is cheap, light, and tough and will not chip or crack when bent, and hence is admirably adapted to the manufacture of hats. Corn-shucks taper in width from butt to tip and their fibers converge toward the tip, and when split the parts separate parallel with the fibers. Hence the divisional parts of the shucks taper and when placed together conform to the increased diameter of the hat with a minimum lap at the longitudinal edges. Corn-shucks when properly cured are tough and can be folded without cracking and are susceptible of assuming any shape, especially when dampened.

For a full description of the invention and the merits thereof and also to acquire a knowledge of the details of construction of the means for effecting the result reference is to be had to the following description and drawings hereto attached.

While the essential and characteristic features of the invention are susceptible of modification, still the preferred embodiment of the invention is illustrated in the accompanying drawings, in which—

Figure 1 is a perspective view of a hat embodying the invention. Fig. 2 is a transverse

section. Fig. 3 is a sectional perspective of a side portion of the hat. Fig. 4 is a detail view in perspective, showing the manner of overlapping and interlocking the finished ends of adjacent elements. Fig. 5 is a detail view of an element, showing the initial fold at the pointed end. Fig. 6 is a view of the part shown in Fig. 5, showing the folded end rebent or folded a second time. Fig. 7 is a detail view of an element, showing the upturned point. Fig. 8 is a perspective view of a modification, parts being broken away.

Corresponding and like parts are referred to in the following description and indicated in all the views of the drawings by the same reference characters.

The brim and tip of the hat comprise a series of courses each, the end portions of the courses being overlapped. The elements entering into the formation of the courses are similarly arranged and shaped. While the hat is particularly designed for the utilization of corn-shucks, it is to be understood that any selected material may be employed in the formation of a hat in accordance with this invention. The tip of the hat comprises a plurality of courses, the outer ends of the elements of one course overlapping the inner ends of the elements of the other course. The inner ends of the element of the innermost course are concealed by a finishing-piece 1, stitched or otherwise secured to the tip. To give a unique and novel appearance to the hat, the outer ends of the elements of the several courses are pointed, as shown at 2, these points being formed in the manner presently to be described. The tip is stiffened and strengthened by a lining 3, of stout paper or other selected material adapted for this purpose.

The brim is composed of upper and lower courses, with an interposed lining 4, to which the elements of the said courses are secured by stitching or other means. The under brim 5 consists of but one course, and the elements 6 have their outer ends folded over the rim 6 and their inner ends bent to lie against the inner face of the lining 7 of the side crown. The upper brim is composed of a series of courses, the outer ends of the elements of the

outermost course overlapping the outer bent ends 8 of the under-rim elements 5, stitched thereto. The inner ends of the elements of the innermost course of the upper brim are 5 bent to lie against the outer face of the lining 7, as shown at 9, and are stitched thereto and to the inner bent ends 10 of the under-brim elements 5. The elements 11, forming the outer course or layer of the side crown, 10 overlap the bent ends 9 of the elements comprising the inner course of the upper brim. The lower ends of the elements 11 touch the upper brim at the angle formed between the brim and side crown, and the upper ends of 15 the elements 11 are bent over the square, so as to overlap the outer portion of the tip-lining 3, to which it is stitched by the thread, securing the pointed ends of the outermost elements of the tip to the lining 3.

20 From the foregoing it will be understood that the side crown comprises elements 11 and parts 9 and 10, and it is stiffened and strengthened by the lining 7, which is confined between the bent ends 9 and 10 of the brim elements. The side crown is finished by having 25 a band 13 applied thereto, and this band is composed of sections having their ends lapped and their overlapping ends pointed. This band 13 is formed of corn-shucks or material 30 similar to that entering into the formation of the hat.

As previously stated, the courses of the tip and brim are composed of elements 14, which are placed together so as to lap at their longitudinal edges, the several elements being 35 secured together by rows of stitching, as indicated. The outer ends of the elements are pointed, as shown at 2, and these points are formed by folding an end portion of the element 40 14 so as to project from the body of the element at an angle, as indicated most clearly in Fig. 5. The bent end 15 is again folded upon itself, so as to lie parallel with the body of the element, as indicated in Fig. 45 6, thereby completing the point. In assembling the elements the outer end portion of each is passed between the bent end 15 and the body of the element adjacent, thereby resulting in the provision of a neat finish and 50 substantial joint.

It will be observed that the joint between the side crown and the tip and brim is substantial, also that the shape of the hat is preserved by the linings 3, 4, and 7. The 55 tip-lining 3 overlaps the side crown-lining 7 and is supported thereby. Attention is also directed to the further support of the lining 3 by the free ends of the bent portions 10 of the under-brim elements 5, which normally 60 stand a short distance from the lining 7 and engage with the lining 3. The hat is finished in any desired way and is provided with the usual sweat-band 16 and inner crown-lining 17.

65 An essential feature of the invention resides in the arrangement of the elements entering into the formation of the courses, said

elements being radially disposed and secured together in series and to the respective linings by rows of stitching. The linings form 70 a base for the reception of the elements, thereby enabling the latter to be placed in position one at a time in successive order.

Some of the courses, preferably the outer ones, have upturned points 18, formed by 75 folding the elements and arranging the folds to stand upward and gradually sloping the parts adjacent to fold to the plane of the brim or tip.

In the construction shown in Fig. 8 the tip, 80 side crown, and brim are separately formed, each being covered by a single course of shuck elements, and the parts are fitted together and stitched through the angle or square formed at the juncture of the parts. 85

Having thus described the invention, what is claimed as new is—

1. As a new article of manufacture, a hat formed of corn-shucks having an approximately radial arrangement and lapped at 90 their longitudinal edges and secured to one another by parallel rows of stitches, substantially as set forth.

2. A hat comprising a lining, corn-shucks or like elements arranged upon the lining in 95 about radial lines and lapped at their longitudinal edges, and parallel rows of stitches securing the radial elements to one another and to the lining, substantially as set forth.

3. A hat comprising elements arranged in 100 courses and in parallel and radial disposition, the courses and the longitudinal edges of the elements being overlapped, and rows of 105 stitches securing the elements and the courses together, substantially as specified. 105

4. A hat comprising courses, each course being composed of elements having their outer ends folded and having their longitudinal edges lapped with a portion of the underlapped edge secured between the overlapped 110 part and the bent end of the elements, substantially as set forth.

5. A hat comprising courses, each course being composed of radially-disposed elements having their outer ends folded and rebent 115 providing points, substantially as set forth.

6. In a hat comprising a tip and side crown, inner and outer elements comprising the side crown, the outermost elements having their upper ends bent over the square and secured 120 to the tip, substantially as set forth.

7. In a hat, a tip comprising a lining and an outer covering, and the side crown comprising a lining and inner and outer elements, the upper ends of the outermost elements being bent to overlap the tip-lining and secured 125 between said lining and covering, substantially as set forth.

8. In a hat, comprising a crown and a brim formed of an upper and an under brim, the latter having its outer portion bent over the brim and having its inner portion bent to lie against the inner face of the side crown, and the upper brim having its outer portion over-

lapping the outer bent end of the under brim and secured thereto and having its inner portion bent to lie against the outer face of the side crown and secured thereto and to the 5 inner bent ends of the under brim, substantially as set forth.

9. In a hat comprising a crown and a brim, the side crown comprising a lining and the brim comprising a lining and an upper and a 10 lower brim, the under brim being composed of elements lapped at their longitudinal edges and having their outer ends bent over the rim and their inner ends bent up against the inner face of the side crown, and the upper 15 brim being composed of courses, each course being composed of elements lapped at their

longitudinal edges and the ends of the outermost elements being stitched through the bent ends of the under-brim elements and the inner ends of the elements of the innermost course being bent to lie against the outer face of the side crown and the said bent ends of the upper and under brim elements being stitched together through the side crown, 20 substantially as set forth.

25 In testimony whereof I affix my signature in presence of two witnesses.
